UNITED STATES PATENT OFFICE.

JOSEPH ALFRED MILLS, OF BEESTON, ENGLAND.

KNITTING-MACHINE.

1,147,531.

Specification of Letters Patent. Patented July 20, 1915.

Application filed May 7, 1914. Serial No. 836,995.

To all whom it may concern:

Be it known that I, JOSEPH ALFRED MILLS, a subject of the King of Great Britain, and a resident of Beeston, in the county of Nottingham, England, have invented new and useful Improvements in Knitting-Machines, of which the following is a specification.

This invention relates to improvements in and applicable to circular knitting machines 10 provided with latch needles and of the automatic type designed for the knitting of stockings and socks.

The present invention has for its object an improved form of stitch cam fitted to oscillate and to slide to and from the needle cylinder whereby the heel and toe of a stocking or sock can be knitted upon the long butted needles instead of upon the short butted needles as is usual and by the use of which 20 stitch cam it is rendered unnecessary to move the instep needles out of and into action at the commencement and completion of a heel and toe, also the combination with such improved stitch cam of pickers for 25 moving the heel and toe needles out of and into action during the knitting of the heel and toe and of improved means by which the splicing thread can be positively fed to the long or short butted needles without the 30 use of a movable thread guide.

In the drawings, Figure 1. is the plan of a cam cylinder constructed according to this invention. Fig. 2. is the development of part of a machine with the needle cylinder 35 removed. Fig. 3. is a section of the improved stitch cam carrying bracket and connected parts. Fig. 4. is a section of the cam cylinder showing also a long butted needle stem. Fig. 5. is a section of the cam cylinder showing also a short butted needle 40 stem. Fig. 6. is an elevation of the down picker guide, and Fig. 7. is an alternative arrangement of splicing selective cams.

In circular knitting machines of the automatic type fitted with latch needles and as usually constructed the needles are divided into two sets of about equal numbers. The instep set of needles have long butts, and at the commencement of the knitting of the 50 heel and toe these needles have to be moved to miss the knitting cams and brought into position to engage the knitting cams at the completion of the heel and toe. For thus moving the long butted needles, upthrow and downthrow cams are provided, and also mechanism by which such cams can be

moved into and out of their operative positions.

According to this invention the needle cylinder 1 is provided with a set of needles 2 which have long butts 3, Fig. 4, and upon these needles the heel and toe are knitted. There is also a set of needles 4 which have short butts 5, Fig. 5, and both sets of needles are actuated for circular knitting by a stitch cam 6, mounted upon an axle 7 which is so carried in the boss 7^a of a bracket 8 carried by the cam cylinder 9 that it can be drawn away from the needle cylinder to miss the short butted needles and allow of these needles being left in their ordinary clearing position during the knitting of the heel and toe of the stocking.

The drawings illustrate the application of this invention to a machine fitted with a rotating cam cylinder 9 which is mounted and actuated according to any usual method. The cam ring 10 is cut away to form up-throw cams 11 and 12 for reciprocal knitting and its upper edge may have a single 80 face 13 as shown in Fig. 7, or a lower face 14 and higher face 15 as shown in Figs. 1, 2, 4, and 5, when this ring is to be used as a means for selecting the needles to which a splicing thread is to be fed.

The axle 7 carrying the stitch cam 6 is located between the up-throw cams 11 and 12 and has end bearings in the boss 7^a of the fixed bracket 8 and is so fitted that it can slide and oscillate in such bearings, a spring 16 tending to hold the stitch cam in its most forward position. Fixed to the outer end of the axle there is a lever 17 fitted with a truck 18 by and through which the stitch cam is oscillated for reciprocal knitting. The boss 7^a is provided with a fixed flange 19 and with a disk plate 20 which is free to turn upon the boss. There is also a cylinder 21 provided with a flange 22 and with a key 23, Fig. 1, which engages with a slot in the 100 boss 7^a and prevents rotation of the cylinder but allows end movement of the same. The disk 20 is provided with two or more inclined pins or cams 24 which engage with suitably shaped slots in the cylinder flange 105 22, so that when the disk 20 is turned the cylinder 21 is forced backward, and through the lever 17 draws the cam 6 clear of the short butts 5. The lever 17 is also fitted with a cam 25 which works in conjunction 110 with a pin 26 on the end of the cylinder 21, these parts being so designed that when the

lever is actuated to change the position of the cam 6, this cam is drawn back to miss the cylinder and returns to its forward position under the action of the spring 16 after it has passed its central position.

At the lower part of the disk 20 there is an arm 26^a provided with a projecting pin 27 by which the disk is actuated through stops which are moved into and out of the path 10 of the pin 27 by pattern mechanism, also the machine is provided with stops or inclines which are moved into and out of the path of the truck 18 for actuating the lever 17, the stops and inclines herein referred to being 15 constructed, arranged and operated in the same way as similar parts in an ordinary knitting machine.

The machine is provided with sinkers 28, which are of any suitable type, and the latch 20 guard ring 29 is provided with a knitting thread hole 30 and a splicing thread hole 31, the latter being higher and in a more advanced position than the hole 30. In the arrangement shown in Fig. 2, the short butted 25 needles are raised by the upthrow cam 12 on to the lower face 14 on the cam ring, in which position the hooks of the needles are below the splicing thread hole 31 and therefore miss the splicing thread. The long 30 butted needles however are raised to the high face 15 on the cam ring, and the hooks of the needles are high enough to take the splicing thread in addition to the knitting threads, which is taken later. In the arrangement indicated in Fig. 7, the cam ring 35 has a single high level face 18 and all the needles are raised sufficiently high to take the splicing thread. With this form of cam ring the machine is fitted with cams 32 and 33 which are slidable to and from the needle cylinder. If the cam 32 is partly advanced it depresses the long butted needles and the splicing thread is fed to the short butted needles. If the cam 32 is fully advanced and the cam 33 is partly advanced, all the needles are depressed by the cam 32 and the long butted needles are afterward raised by the cam 33 to take the splicing thread. Cams similar to 32 and 33, but placed at reversed 40 angles, may also be used for selecting the needles to receive the splicing thread in connection with a single face low level cam ring.

The machine is fitted with needle picking up fingers 34 and 35 and with a needle picking-down finger 36, and these fingers are designed to pick up one needle at a time during the knitting of the first part of the heel and toe, and to pick down two needles and pick up one needle during the knitting 50 of the second part of the heel and toe according to one of the usual methods of knitting the heel and the toe. The finger 34 is mounted upon a horizontal axle 37 which is carried by a block 41 capable of turning on a vertical axle 38. The front end of the finger

rests upon an inclined guide 39 and is held in contact with such guide by a spring 40 on the axle 37. During ordinary knitting the needles rising up the cam 12 pass under the picker 34 but when the cam cylinder 70 reciprocates in the opposite direction to the direction of circular knitting the long butted needles pass from the face 15 into contact with the picker and force this picker up the incline guide until the butts are high enough 75 to pass over the top of the stitch cam 6 by which time the picker passes from under the butt and returns to its normal position. The finger 35 is similar in construction and action to the finger 34, and for the purpose 80 of holding it clear of the needles during circular knitting, its block 41 is provided with a projecting pin 42 and there is a plate 43 carrying upright pins 44 and fitted to turn on the axle 38. The plate 43 is connected by 85 links 45 and 46 to an arm 47 on the disk 20 and these parts are so arranged that when the stitch cam 6 is in position for circular knitting the picker 35 is held clear of the needles. When however the disk 20 is 90 turned to withdraw the cam 6 clear of the short butted needles the picker 35 is released and acts to pick up the needles in the same way as the picker 34.

The down picker 36 works within a double 95 inclined guide 48 and is mounted in a block 51 similarly to the up pickers. During circular knitting the picker 36 is held in the position shown by a lever 49 and spring 100 actuated catch 50, but when released by the pattern mechanism from the holding catch the picker is moved by its spring 52 to the highest position in the guide shown in Fig. 6, and moves to the right and left of such position alternately, being returned to its 105 highest position after each picking action.

The drawings illustrate the positions of the various parts when the cam cylinder is being rotated, in the direction of the arrow π , Fig. 1, for circular knitting. When it is 110 desired to change to reciprocal knitting, as when the heel and toe of a stocking are being produced, the disk plate 20 is operated to shift the stitch cam to such a position that it will clear the needles having short 115 butts, and this is done on the last revolution of the cylinder and when the stitch cam is acting upon the needles provided with long butts. The cam cylinder completes its last revolution when the stitch cam 6 is opposite 120 the short butts, which are then in their clearing position, and the cam is turned for the first reciprocal movement, and is changed from one position to another at the end of each succeeding reciprocal movement of the cam cylinder. At the completion 125 of the reciprocal movements the disk plate 20 is returned to its normal position to allow the stitch cam to move forward to engagement with the short butts, and it may 130

be so turned either when it is in engagement with the long, or when opposite to the short, butts, although in the latter case the cam would rub upon the ends of the short butts 5 until it engaged the long butts and was free to be moved forward by the spring 16.

The various mechanisms herein referred to are described as designed for use in automatic knitting machine fitted with a rotating cam cylinder, but they are equally applicable to machines fitted with a stationary cam cylinder and a rotating needle cylinder, also, the improved stitch cam can be used in connection with any ordinary circular 10 latch needle knitting machine in which it is necessary, or desirable, that the stitch cam can be moved away from the needle cylinder to allow of such cylinder being readily removed from the machine.

20 In addition to the mechanism herein described there are suitable springs and catches for moving the parts in one direction and for holding them in the desired positions and such parts are arranged in accordance with the usual practice. The machine is also provided with work take up mechanism, thread tension devices, and other usual and necessary parts of an automatic knitting machine.

30 What I claim is, in a circular latch needle automatic knitting machine,

1. The combination of a needle cylinder carrying a set of long butted needles and a set of short butted needles, a cam cylinder 35 having a right hand up-throw clearing cam and a left hand up-throw clearing cam, and a stitch cam located between these up-throw cams arranged to be turned to coöperate with either of them and supported so it 40 may be moved toward the needle cylinder to operate upon all the needles or away from the needle cylinder to operate only upon needles with long butts.

2. The combination of a needle cylinder 45 carrying a set of long butted needles and a set of short butted needles, a cam cylinder, a stitch cam supported so as to oscillate and also to slide toward and away from the needle cylinder, and means arranged to 50 cause the stitch cam to move back from the needle cylinder as it is oscillated to change its position, whereby it clears the cylinder during such movement, and then to move

toward the needle cylinder into operative position.

3. The combination of the needle cylinder, a set of long butted needles, a set of short butted needles, a stitch cam fitted to oscillate and slide, the cam ring, a low face on such ring for the short butted needles, a 60 high face on the ring for the long butted needles, a latch guard ring, and a knitting thread hole and a splicing thread hole in such ring substantially as herein described.

4. The combination of the needle cylinder, 65 needles in such cylinder, a cam ring, a stitch cam, a bracket carrying such stitch cam, a boss on the bracket, a rotatable disk on such boss, a slidable cylinder mounted upon the boss, cam pieces attached to the rotatable 70 ring, cam slots in the cylinder flange, a lever on the stitch cam axle, a cam on the lever, a co-acting pin on the end of the cylinder, and a spring tending to keep the stitch cam in its most forward position substantially as 75 herein described.

5. The combination of a needle cylinder, a set of long butted needles, a high face on the cam ring for raising the long butted needles high enough to take a splicing 80 thread, and the knitting thread, a set of short butted needles, a low face on the cam ring for raising the short butted needles high enough to take the knitting thread only, a stitch cam which can oscillate and 85 be drawn back to miss the short butts during reciprocal knitting, a latch guard ring, and a knitting thread hole and a splicing thread hole in such ring substantially as 90 herein described.

6. The combination of the needle cylinder, a set of needles with long butts, a set of needles with short butts, a knitting cam ring, a stitch cam which can oscillate and slide, a picking down finger, two picking up 95 fingers, means for holding one picking up finger out of action, connections between such means and the means for holding the stitch cam clear of the short butted needles, and the means for holding the stitch cam in 100 such position substantially as herein described.

JOSEPH ALFRED MILLS.
